UNITED STATES PATENT OFFICE.

CHARLES F. McBEE, OF ATHENS, OHIO, ASSIGNOR TO THE McBEE BINDER COMPANY, OF ATHENS, OHIO, A CORPORATION OF OHIO.

LOCKING DEVICE FOR LOOSE-LEAF FILES OR BINDERS.

Application filed August 4, 1920. Serial No. 401,171.

To all whom it may concern:

Be it known that I, CHARLES F. McBEE, a citizen of the United States, residing at Athens, county of Athens, and State of Ohio, have invented a certain new and useful Improvement in Locking Devices for Loose-Leaf Files or Binders, of which the following is a specification.

My invention relates to that class of loose-leaf binders which are designed to bind a number of leaves and which will permit the insertion of additional leaves or the removal of leaves from the binder without destroying or disarranging the other leaves.

My invention has for its object to provide a filing and locking device in which the leaves may be inserted even though the perforations are not in alignment with the rods on which they are mounted, and to accomplish this result, I employ upwardly extending flexible rods which can be bent to fit the perforations of the loose-leaves, and which when locked, forms a very rigid and secure binder.

My means of accomplishing the foregoing objects may be more readily understood by having reference to the accompanying drawings which are hereunto annexed and made a part of this specification in which—

Fig. 1 illustrates a loose-leaf file or binder equipped with my new invention.

Fig. 2 is a top or plan view showing the locking device.

Fig. 3 is an enlarged detail view of my new improvement.

Similar reference numerals refer to similar parts throughout the entire description.

As shown in the drawings, I provide two covers which may be of any size, the lower cover 10 of which has fixedly secured thereto and adjacent its ends, two upwardly projecting flexible rods 11 and 12 which can be bent to fit the loose leaves 13.

It is apparent that any number of flexible rods may be employed that I do not desire to limit myself to the employment of two rods. I provide a metal strip I-shaped in cross-section 16 which is perforated, said perforations 18 and 19 being adapted to receive the flexible rods 11 and 12 which can be bent again to fit the perforations in the metal strip 16, if they are not in register therewith.

The upper cover 26 is provided with a

metal strip 20 which is secured to the inside 55 of the upper cover 26. This strip is provided with longitudinally inturned flanges 21 and 22 and outwardly extending flanges at each end 23 and 24.

The operation of my device is as follows: 60

When the operator is ready to bind his papers, he bends the flexible rods 11 and 12 until they fit the perforations in the loose leaves 13 which are slid over the rods. The rods are then bent so as to register with the 65 perforations in the strip 16 which is then slid over these rods until it rests against the leaves 13. The book, magazine or file is now ready to be bound. The metal strip 20 slides over the metal strip 16 as clearly 70 shown in the drawings, the longitudinally inturned flanges 21 and 22 guiding the metal strip 16 and holding it in position. The metal strip on the upper cover is preferably 75 made of flexible material so that the outwardly extending flanges 23 and 24 can be bent down so as to securely lock the same. The flexible rods 11 and 12 are bent and are folded so as to lay flat over the I-bar. It 80 will be apparent from the foregoing that this enables the file to be securely locked and cannot be unbound until the operator pulls the upper cover off. While I have shown and described specific means employed to utilize my invention, I do not desire to limit myself 85 to the exact construction, it being apparent that other means may be employed to use my invention.

Having described my invention what I regard as new and desire to secure by Letters Patent is:

A loose-leaf binder comprising the combination with an upper and lower cover, the lower cover having vertical, flexible rods adjacent its ends in spaced relation, adapted to 90 receive the sheets to be filed, a metal bar, I-shaped in cross-section, there being perforations in said bar adapted to receive the flexible rods, a metal strip secured to the inside of the upper cover provided with longitudinal inturned flanges and outwardly extending flanges at each end, said strip being 95 adapted to slide over the sides of the I-bar and rods.

In testimony whereof, I have signed the 100 foregoing specification.

CHARLES F. McBEE,
